US00D915196S

(12) **United States Design Patent** (10) Patent No.: **US D915,196 S**
(45) Date of Patent: ** Apr. 6, 2021

(54) **PACKAGE AND PACKAGING SHEET FOR FOODSTUFF**

(71) Applicant: **TETRA LAVAL HOLDINGS & FINANCE S.A.**, Pully (CH)

(72) Inventors: **Giacomo Gaudiomonte**, Modena (IT); **Marcello Barbieri**, Modena (IT); **Davide Morciano**, Modena (IT); **Elisa Michelini**, Modena (IT); **Francesco Fontanazzi**, Modena (IT); **Alberto Mameli**, Modena (IT); **Carlo Forcellini**, Modena (IT)

(73) Assignee: **TETRA LAVAL HOLDINGS & FINANCE S.A.**, Pully (CH)

(**) Term: **15 Years**

(21) Appl. No.: **35/506,937**

(22) Filed: **Dec. 14, 2018**

(80) **Hague Agreement Data**

Int. Filing Date: **Dec. 14, 2018**

Int. Reg. No.: **DM/201464**

Int. Reg. Date: **Dec. 14, 2018**

Int. Reg. Pub. Date: **Jun. 21, 2019**

(30) **Foreign Application Priority Data**

Jun. 14, 2018 (EM) 005311016

(57) **CLAIM**

The ornamental design for package and packaging sheet for foodstuff, as shown and described.

DESCRIPTION

11. Package for foodstuff
12. Packaging sheet for foodstuff
11.1 : Front perspective view
11.2 : Front view
11.3 : Rear view
11.4 : First side view
11.5 : Second side view
11.6 : Top view
11.7 : Bottom view
12.1 : Front perspective view
12.2 : Front view
12.3 : Rear view
12.4 : First side view
12.5 : Second side view
12.6 : Top view
12.7 : Bottom view

The broken lines in the drawings illustrate portions of the package and packaging sheet for foodstuff that form no part of the claimed design.

The packaging sheet for foodstuff illustrated 12.1-12.7 in corresponds directly to the package for foodstuff illustrated

(Continued)

in reproductions 11.1-11.7. The packaging sheet for foodstuff illustrates the corresponding package for foodstuff in collapsed form.

1 Claim, 14 Drawing Sheets
